US00D900269S

(12) **United States Design Patent** (10) **Patent No.:** **US D900,269 S**
(45) **Date of Patent:** **** Oct. 27, 2020**

(54) **FIREARM PISTOL BRACE**

(71) Applicant: **George Huang**, Henderson, NV (US)

(72) Inventor: **George Huang**, Henderson, NV (US)

(73) Assignee: **Battlearms IP, LLC**, Henderson, NV (US)

(**) Term: **15 Years**

(21) Appl. No.: **29/671,553**

(22) Filed: **Nov. 28, 2018**

(51) **LOC (12) Cl.** **22-01**

(52) **U.S. Cl.**

USPC **D22/108**; D22/111

(58) **Field of Classification Search**

USPC D22/100, 103, 104, 105, 108, 109, 110, D22/111, 199; D21/567, 573, 574, 575

(57) **CLAIM**

The ornamental design for a firearm pistol brace, as shown and described.

DESCRIPTION

FIG. 1 is an upper, rear, right isometric view of a firearm pistol brace, showing my new design;

FIG. 2 is an upper, rear, left isometric view thereof;

FIG. 3 is a lower, rear, right isometric view thereof;

FIG. 4 is a lower, rear, left isometric view thereof;

FIG. 5 is an upper, front, right isometric view thereof;

FIG. 6 is an upper, front, left isometric view thereof;

FIG. 7 is a right side view thereof;

FIG. 8 is a left side view thereof;

FIG. 9 is a rear view thereof;

FIG. 10 is a front view thereof;

FIG. 11 is a top view thereof; and,

FIG. 12 is a bottom view thereof.

The broken lines shown throughout the various figures depict unclaimed portions of the brace only, which form no part of the claimed design.

1 Claim, 6 Drawing Sheets
